METHOD AND APPARATUS FOR PACKAGING BEVERAGES

Samuel Henry Ayers, Philadelphia, Pa., assignor to Crown Cork & Seal Company, Inc., Baltimore, Md., a corporation of New York

Application October 25, 1938, Serial No. 236,948

19 Claims. (Cl. 226—82)

The present invention relates to methods and apparatus for packaging beverages and, more particularly, to the removal of air from receptacles containing beverages.

The principal object of the invention is to provide a method and apparatus for removing air from the head space of a receptacle containing a carbonated beverage, such as a beer or a soft drink.

In filling containers with carbonated beverages, and particularly beer, it is highly desirable to exclude air from the head space of the container, since it is found that the oxygen of such air causes, or at least accelerates, changes in the flavor and turbidity of the beer.

Various means have been used to expel the air from the container head space, but all such methods heretofore proposed have involved certain variable factors. For example, one previous method has involved tapping each bottle during its movement on the filling machine from the filling mechanism to the crowning mechanism, the tapping means being arranged to strike each bottle and thereby agitate the contents so that carbon dioxide would be liberated to expel the air from the head space just prior to crowning. The difficulty with this method has been that since the walls of the main or body portions of bottles of the same rated capacity may vary rather widely in thickness, the tapping mechanism had to be adjusted to strike the thickest possible container sufficiently sharply to agitate the contents to the necessary extent. As a result, a bottle having a relatively thin wall would receive too sharp a blow, with the possibility that the beer therein would be agitated to such an extent that uncontrolled foaming would occur, with resultant waste.

By the method and apparatus of the present invention, heat is applied either directly to the contents of the container or to a localized area of the container to liberate carbon dioxide from the beverage to force the air from the container head space, so that when the container is subsequently sealed, substantially no air will be contained in the container with the beverage.

The method and apparatus of my invention, involving the application of heat directly to the gas containing beverage, or to a localized area of the container, avoids all variable factors encountered in the use of prior apparatus and methods. For example, the temperature of a beverage, when flowed into a container, can be readily controlled, and the gas content of any batch can also be readily ascertained. Thus if

the temperature of the heat employed in my invention is controlled, and also the length of application of heat, no variable factors will be involved and substantially all air will be positively forced from the head space of the container. Where the heating by my invention involves the immersion of some heating means in the beverage, the depth of such immersion can also be made a constant factor.

By my invention, bubbles will rise from the liquid to form a foam which is stable, as distinguished from ordinary uncontrollable foaming similar to boiling. The foam formed by the present invention, particularly on beer, will remain in place for several minutes and, in every instance, will remain in place until the container can be sealed.

Thus, by the use of the method and apparatus of the present invention, only sufficient inert gas will be liberated from the beverage to substantially remove all air from the container head space and I obviate all possibility of undesirable foaming; that is, such foaming as will continue indefinitely.

Other objects and advantages of the invention will be apparent from the attached drawings, wherein:

Figure 1 is a horizontal sectional view taken above the work table of a filling machine and showing a mechanism of the present invention applied to the machine;

Figure 2 is a vertical sectional view on the line 2—2 of Figure 1;

Figure 3 is a detail view showing a modified form of heating element;

Figure 4 shows an arrangement similar to that of Figure 2 but with provision for immersing water-heated coils in the containers;

Figure 5 is a vertical sectional view of a can of beer or other carbonated beverage showing the manner of immersing a heated coil therein, as by the structure of Figure 4;

Figure 6 is a view similar to Figure 5 but showing the can at the completion of the heat applying operation;

Figure 7 is a horizontal sectional view taken above the work table of a filling machine of well-known construction and showing a modified arrangement for heating containers;

Figure 8 is a vertical sectional view on the line 8—8 of Figure 7, and

Figure 9 is a view in vertical section showing a mechanism for partially immersing containers in suitably heated water.

Referring to Figures 1 and 2, the numeral 10

designates the stationary work table of a filling machine, which filling machine comprises a rotary filling mechanism 11 and a crowning mechanism 12. In the embodiment of the apparatus disclosed, a transfer dial 13 removes bottles or cans from the filling platforms of the filling table 11 and positions them upon a rotary table 14 fixed to a hollow shaft 15 which rotates about a vertical post 16. A dial 17 is fixed to shaft 15 just above the rotary table 14 to hold the containers properly positioned while a heating means 18 descends into the bottle to liberate gas. When the heating is completed, the heating means will rise and the container will be removed from table 14 by a second transfer dial 19 which will move the container to the rotary table 20 of the crowning or sealing mechanism 12. All of the above mechanisms are continuously rotated.

The post 16 extends above the dial 17 and supports a circular cam track 21 including a depressed portion 22. A casing 23 is rotatable upon the post 16 with table 14 and dial 17, casing 23 having a plurality of vertical bores therein in which the heating elements or means 18 are vertically movable, one element 18 being aligned with each pocket of the dial 17. Each element 18 carries a roller 24 which engages the cam track 21. The depressed portion 22 of the cam track is so positioned that the rotation of the casing 23 with respect to the cam track 21 will cause the heating elements 18 to be successively moved downwardly into a container beneath the same just after the container moves onto the table 14, the heating element being raised or retracted from the container just prior to movement of the container from the table 14 to the dial 19.

Figure 2 shows an arrangement for supplying electric current to each element 18. By the structure shown in Figure 2, each element 18 would have a resistance coil therein, one side of the coil being grounded to the machine and the other side being connected through the rod 26 to a brush element 27 which bears upon a stationary sleeve 28 secured to and insulated from the upper end of the post 16. Sleeve 28 is connected to one side of a suitable power circuit through a lead 29. A thermostatic element 30 is provided in the circuit, this element being of such design that the heating elements 18 will be maintained at a constant temperature of from about 140° F. to about 210° F., depending upon the period within which it is desired to produce the foam and the quantity of foam which is to be produced, bearing in mind that different types of containers of like capacity differ widely as to head space. The rods 26 are adjustably secured in the sleeves 31 which carry the rollers 24 so that the depth to which the rods will be immersed in the contents of the container may be adjusted and fixed. The adjustable mounting of the rods 26 may be accomplished, for example, by threading them in the sleeves 31 or by use of set screws, not shown. The cam track 21 may also be adjustable by inserts, not shown, to enable the period during which the heating element is immersed in a container to be changed.

Generally speaking, it is desirable to postpone heating of the liquid until any foam formed during filling has broken, so that the liquid will have a quiet surface.

Figure 3 shows a modified form of heating element comprising a tube 35 having apertures at its lower end through which steam may issue

into the upper portion of the contents of the container. The tube 35 would be mounted for vertical movement in the same manner as the element 18 of Figure 2 and would be supplied with steam through flexible lines and a manifold in any desired manner. In some cases, the supply of steam to the elements 35 would be controlled by a slide valve arrangement so that steam would only be projected from the lower end of the element 35 when such end is immersed beneath the surface of the contents of the container. In any event, a means to maintain the elements at the desired constant temperature would be provided in the steam supply line. Also, the steam would be carefully controlled to assure of its being free of air. Particular care must be exercised in the period of immersion of the steam jet to avoid uncontrollable foaming, but this is a very desirable method of producing localized heating when very rapid action is required, such as in bottling and capping at high speed production. Injection of a very small amount of steam causes quick release of gas, and the jet may be inserted into the beverage for a very short length of time and then withdrawn, following which the foam builds up and fills the head space. This may be of particular advantage in foaming beverages packed in long, narrow necked bottles, since the jet may be withdrawn and the foaming quickly fills up the space created by withdrawal of the heating element.

By each of the structures described above, heat would be applied directly to the liquid in the upper portion of the container, heating this liquid sufficiently to cause local release of carbon dioxide; i. e., a release of carbon dioxide from the upper portion of the liquid, and at a rate insufficient to involve uncontrollable foaming. Such carbon dioxide will rise in the head space 40 of the container as a foam which, at least with beer, is extremely fine. In any event, the foam being heavier than the air present in the head space, will force the air from the head space. Immediately thereafter, the container will be 45 sealed or crowned by the crowning mechanism 12. It will be noted that during the travel of the container about the dial 19, the carbon dioxide will have an opportunity to further rise in the head space of the container prior to crowning. However, due to the complete and exact 50 control of the generation of carbon dioxide possible by the present invention, the carbon dioxide can be caused to rise rather suddenly and yet without possibility of uncontrollable foaming, thereby permitting the bottles to be crowned immediately after the application of heat, and without the interpositioning of the dial 19 between the device carrying the heating elements and the crowner 12.

Figure 4 shows a structure adapted to be applied to a filling machine in the same manner as the structure of Figure 2 except that the slides 31a carry depending U-shaped coils 52 through which water is circulated. A tank, heating means and pump, not shown, supply the water through a supply line 55 leading to an angled bore 56 in a manifold 57 fixed to the non-rotatable center post 16a. The opposite end of bore 56 opens to a circumferential channel 58 in manifold 51 to 60 supply water to ports 59 in a sleeve 60 which rotates with the casing 23a and the slides 31a. A flexible tube 61 is connected to each port 59, the opposite end of the tube 61 being connected to a bore in the corresponding slide 31a, which 70 bore communicates with one end of the corre-

sponding U-shaped coil 52 so that hot water will be supplied to the latter. The opposite leg of each coil 52 opens to a second bore in the slide, which bore has a flexible tube 62 connected thereto which communicates with a port 63 in the sleeve 60. The ports 63 open to a second circumferential channel 64 in manifold 57, and channel 64 communicates with a bore 65 with which a return pipe 66 is connected to conduct the water back to the heated supply tank. With the slides 31a reciprocating in the same manner as the slides 31 of Figure 2, a water heated coil 52 will be immersed in each container moving from the filling mechanism to the sealing or crowning mechanism.

Figure 5 shows a coil 52 immersed in beer or other carbonated beverage within a wide mouthed can. As indicated, the hot water at a temperature of from about 140° F. to about 210° F., depending upon the temperature of the beverage, and preferably at a temperature of from 140° to 150° F. where the beverage temperature is about 45° F., causes small foam bubbles to be formed, particularly adjacent the coil. These bubbles rise to the top of the liquid and, with the preferred temperature, within from twenty to ten seconds, (the exact period depending upon the temperature of the heating water, the degree of carbonation, and the temperature of the carbonated beverage) the head space of the container will be filled with bubbles which, at least with beer, are very small. The foam thus produced is quite stable and, particularly with beer, will remain in the head-space for several minutes, an ample period to permit of sealing the container in usual course. It is desirable to so gauge the operation, including the depth of immersion of the element 52, that the foam will rise slightly above the top or mouth of the can or bottle so that when the heating element is withdrawn, and the foam settles into the space thus created, the head-space of the container will still be filled with foam as shown in Figure 6.

In cases where more rapid heating is desired, steam may be circulated through the element 52, instead of hot water.

It will be understood that the devices of Figures 1 to 3 will create foam in the same manner as the device of Figure 4.

It will be understood that instead of moving the heating element toward the containers, the containers may be elevated by a suitable cam to cause a vertically stationary heating element to be immersed in the upper portion of the contents.

It is to be particularly noted that the present invention provides means to control the temperature of the heating element, the time or period during which heat is applied to each container, and also the depth to which a heating element is immersed in the contents. Thus, by controlling the temperature at which the liquid is flowed into the can or bottle, as well as ascertaining the gas content in each batch of liquid filled, no variables enter into the method and apparatus of the present invention.

Figures 7 and 8 show a modified form of heating arrangement wherein heat is applied to a localized portion of the container C. The reference numeral 10a designates the work table of the filling machine including a rotary filling table 11. Containers, preferably cans, are removed from the filling table by a dial 40 which transfers them to the crowning mechanism 12. A tunnel 41 of generally inverted U-shaped form in vertical section overlies the portion of the

transfer dial 40 about which containers move, and the can C will move through this tunnel when traveling from the filling table to the crowning mechanism. As best shown in Figure 8, the tunnel 41 encloses the upper portion of the can and is provided with baffle plates 42 between which the neck of the container passes, the baffles 42 thereby defining, with the top and upper side walls of the tunnel, a chamber 43 through which the upper portions of the bottles pass. Electrical heating units 44 are provided on the inner surfaces of the side walls of the tunnel so that the air within the tunnel is maintained in a heated state. If desired, closed steam coils may be used as the heating means for the chamber 43. Thermostatic means may be provided in the chamber 43 to control its temperature.

By the arrangement shown in Figures 7 and 8 the upper portions of the containers will pass through a body of highly heated air so that the upper portions of the containers as well as the upper portion of the contents of the container will be heated to a sufficient degree to cause carbon dioxide to rise, usually in the form of compact controllable foam, from the upper part of the liquid within the containers.

It is to be noted that the tunnel 41 is kept in a heated state by heating the air therein. The use of heated air is found to be highly desirable since it does not cause such an increase in pressure within the chamber as would prevent carbon dioxide from freely rising from the beverage. For example, if free steam were used within the tunnel, the atmosphere within the tunnel would be under some pressure and, as a result, the carbon dioxide could not readily rise from the beverage.

In some instances, the application of localized heat to other areas than the top portion of the container is found satisfactory; for example, where the beverage is packaged in a can.

Figure 9 shows a mechanism which may be interposed between a filling mechanism and a sealing mechanism to partially immerse a can 45 in a body of hot water for the purpose of the present invention. The numeral 70 designates an endless conveyor to which cans move from the filling mechanism, this conveyor terminating adjacent a tank 71 of suitably heated water. A 50 conveyor 72 is positioned above the outlet end of conveyor 70 and extends over the tank 71. Conveyor 72 has forked hooks 73 pivoted thereto and as the conveyor 72 moves, these hooks will drop from a guide plate 74 to engage about the neck 55 of a filled can on conveyor 70 to move the can from the latter conveyor and carry it through the water in the tank 71. As shown, the central portion of the lower run of conveyor 72 is depressed to lower the can into the tank. The 60 conveyor 72 will place the cans upon a conveyor 75, the hooks 73 being momentarily detained at the instant the can reaches a firm position on the latter conveyor by suitable trip means, not shown, for example, a pivoted arm lightly sprung 65 pressed to momentarily retard advancing movement of the hook so that the can may move out of engagement therewith.

The can is preferably immersed to one-third its height in the water. Such immersion of a 70 can of beer for a few seconds, with the water at a temperature of from 140° to 160° F., depending upon the temperature of the beverage, will cause a compact and stable foam to fill the head space of the container. If the can is immersed to a greater depth, the water temperature may

be reduced. For example, it is found that with a can, one-third immersed in water at 140° F., and with the beverage at 45° F., the head space will be filled with a stable, controllable foam in thirty seconds. With other conditions identical, immersion in water at 160° F. will fill the head space in fifteen seconds.

Comparable operations with regard to the structure shown in Figure 4, show that with the heating coil 52 immersed to one-half the depth of a can of beer, the head space is filled with the desired foam in fifteen seconds with the water temperature at 140° F. while if the water temperature is at 190° F., the head space will be filled with foam in two seconds, both examples assuming that the beverage is at 45° F. A greater heat than indicated, too long applied, is apt to cause the foam to break, permitting air to re-enter the head space.

As hereafter stated, the periods of heating just stated must be reduced with some soft drinks.

It is to be understood that the type of foam which may be created by the present invention, at least with beer, is formed of very fine bubbles and is very compact due to the relatively slow heating, thereby substantially excluding all air from the container head space. It is also extremely stable and will remain in place for several minutes and, when a heating element is withdrawn, will settle into the space thus created. Formation of foam to a slight height above the mouth of the container will assure that such settling does not leave an air-space in the head of the container. This type of foam is also controllable; that is, the formation of the foam will discontinue immediately or almost immediately the application of heat is terminated. All of these characteristics distinguish the foaming obtained by the present invention from the foaming which may occur as the result of a general, as opposed to a localized, application of heat or the tapping or other agitation of the container and contents, for in the latter instances the foaming is sudden and violent and in extremely large bubbles which further increase in size as they move upwardly through the beverage. Also, foaming caused by these last-mentioned methods is uncontrollable and may continue indefinitely so that a large gas or liquid loss may occur and the foam may or may not remain in the head space for a suitable period to permit sealing.

The foam which occurs with beer by the use of the present invention is formed of quite small bubbles and builds up relatively slowly. With most soft drinks, the bubbles are somewhat larger, form more rapidly, and the foam which results is not quite so stable, requiring that the bottle be capped as soon as possible after heating is discontinued, and also that the period of application of heat be reduced. Moreover, the controlled foaming which occurs with soft drinks varies with the different beverages, some foaming more rapidly than others and some, for example, ginger ale, producing a more stable foam.

Subject matter disclosed but not claimed herein may be claimed in my divisional application for Methods and apparatus for packaging beverages, Serial No. 486,570, filed May 11, 1943.

The phraseology employed in the specification is for the purpose of description and is not intended to limit the invention, the scope of the invention being indicated in the claims.

I claim:

1. The method of packaging beverages containing carbon dioxide comprising substantially

filling a container with the beverage in an atmosphere containing air so that the space in the container above the liquid will contain air, raising the temperature of the beverage by inserting a heating means into the beverage sufficiently to liberate carbon dioxide to thereby expel at least a part of the air from the space in the container above the liquid, and then sealing the container.

2. The method of packaging beverages containing carbon dioxide comprising substantially filling a container with the beverage in an atmosphere containing air so that the space in the container above the liquid will contain air, raising the temperature of the beverage adjacent the top of the container by inserting a heating means into the beverage adjacent the top of the container to liberate carbon dioxide and thereby expel at least a part of the air from the space in the container above the liquid, and then sealing the container.

3. The method of packaging beverages containing carbon dioxide comprising substantially filling a container with the beverage in an atmosphere containing air so that the space in the container above the liquid will contain air, raising the temperature of the beverage adjacent the top of the container by inserting a heating means into the beverage adjacent the top of the container to liberate carbon dioxide in the form of fine bubbles to fill the head space of the container, and then sealing the container.

4. The combination in a filling machine, of a container filling mechanism, a sealing mechanism, a heating device mounted for immersion in the upper portion of a container to raise the temperature of the container sufficiently to liberate carbon dioxide and expel at least a part of the air from the space above the contents, and means to actuate said mechanisms and device in timed relation.

5. The combination in a filling machine, of a container filling mechanism, a container sealing mechanism, means to move a container between said mechanisms, a heating element, and means to move the said heating element with respect to the container so that the element will be immersed in the upper portion of the contents to heat the same sufficiently to liberate carbon dioxide from the contents and thereby expel at least a part of the air from the space above the contents.

6. A mechanism for liberating carbon dioxide from a liquid within an open container comprising a support, a steam jetting device, and means to move said device relative to said support and into a container to heat at least the upper portion of the liquid within such container to a sufficient degree to liberate carbon dioxide therefrom.

7. A mechanism for liberating carbon dioxide from a liquid within an open container comprising a support, a heating device movable with respect to said support and adapted to be immersed in the liquid within the container to raise the temperature of the liquid sufficiently to liberate carbon dioxide and thereby expel at least a part of the air from the space above the liquid, and means to move said last-named means with respect to said support and into the liquid.

8. The combination in a filling machine, of a container filling mechanism, a container sealing mechanism, a water-heated element positioned between said mechanisms, and means to immerse said element in the container contents to raise the temperature of the contents sufficiently to

liberate carbon dioxide and expel at least a part of the air from the space above the contents.

9. A mechanism for liberating carbon dioxide from liquid within an open container comprising a support, a water-heated element, and means to move said element relative to said support and into a container to heat at least the upper portion of the liquid within such container to a sufficient degree to liberate carbon dioxide therefrom.

10. The combination in a filling machine, of a container filling mechanism, a container sealing mechanism, a fluid-heated element positioned between said mechanisms, and means to immerse said element in the container contents to raise the temperature of the contents sufficiently to liberate carbon dioxide and expel at least a part of the air from the space above the contents.

11. The method of packaging beverages containing carbon dioxide, which comprises partially filling a container with the beverage, the unfilled space remaining in the container above the liquid level containing air, raising the temperature of only a relatively small proportion of the volume of the beverage in the container to cause it to release part of its carbon dioxide content and thereby purge at least part of the air from the said space above the liquid, and then sealing the container.

12. In apparatus for purging air from the space above the liquid level in a partially-filled carbonated beverage container, the combination of a pathway along which the container is adapted to move, a heating element adjacent the pathway, means for inserting the element in the container to heat at least part of the liquid therein to cause it to liberate gas and thus purge at least part of the air from the container, and means adjacent the pathway for sealing the container.

13. In a system for packaging a liquid containing a gas at least partially releasable therefrom upon increase in temperature, the combination of means for partially filling a container with the liquid, the unfilled space above the liquid level in the container containing air, a tubular heating element, means for supplying a fluid heating medium thereto, means for inserting and then withdrawing said element from the liquid in the container for heating at least part of the liquid so as to liberate gas therefrom and thus purge at least part of the air from the said space above the liquid, and means for then sealing the container.

14. In a system for packaging a liquid containing a gas at least partially releasable therefrom upon increase in temperature, the combination of means for partially filling a container with the liquid, the unfilled space above the liquid level in the container containing air, a heating element including a supply and return tube, means for circulating a fluid medium through the tubes of said element to heat the same, means for im-

mersing said element in the liquid for heating it to cause it to liberate part of its gas content and purge at least part of the air from the said space above the liquid, and means for then sealing the container.

15. In apparatus for purging air from the space above the liquid level in a partially-filled carbonated beverage container, the combination of a support for the container, means for moving the support, a heating element over said support, mechanism synchronized with said moving means for first inserting said element in the liquid in said container and then withdrawing the same, whereby at least part of the liquid is heated to liberate gas therefrom for purging at least part of the air from the container, and means for sealing the container.

16. In a system for packaging a liquid containing a gas at least partially releasable therefrom upon increase in temperature, the combination of means for partially filling a container with the liquid, the unfilled space above the liquid level in the container containing air, means inserted in the liquid for heating at least part of the same to cause it to liberate part of its gas content for purging at least part of the air from the container above the liquid level, and means for then sealing the container.

17. In apparatus for purging air from the space above the liquid level in a partially-filled carbonated beverage container, the combination of a pathway along which the container is adapted to move, a plurality of heating means adjacent the pathway, means for inserting said means in the liquid for heating the same to cause it to liberate gas for purging at least part of the air from the container, and means adjacent the pathway for sealing the container.

18. In apparatus for purging air from the space above the liquid level in a partially-filled carbonated beverage container, the combination of a pathway along which the container is adapted to move, a heating means above the pathway, means for inserting said means through the open top of the container into the liquid therein for heating at least part of the liquid to cause it to liberate gas and purge at least part of the air from the container, and means adjacent the pathway for sealing the container.

19. The combination in a filling machine, of a container filling mechanism, a sealing mechanism, an electrically heated device mounted for immersion in the upper portion of a container to raise the temperature of the container contents sufficiently to liberate carbon dioxide and expel at least a part of the air from the space above the contents, and means to actuate said mechanisms and device in timed relation.

SAMUEL HENRY AYERS.
